UNITED STATES PATENT OFFICE.

ADOLPH R. BLOMBERG, OF KITTERY, MAINE, ASSIGNOR OF ONE-HALF TO ARTHUR C. BARR, OF MANCHESTER, NEW HAMPSHIRE.

EXTENSION-TABLE.

1,057,114.

Specification of Letters Patent.

Patented Mar. 25, 1913.

Application filed March 14, 1911. Serial No. 614,297.

To all whom it may concern:

Be it known that I, ADOLPH R. BLOMBERG, a citizen of the United States, residing at Kittery, in the county of York and State 5 of Maine, have invented new and useful Improvements in Extension-Tables, of which the following is a specification.

The present invention has relation to tables of the variety adapted to be lengthened 10 or shortened to meet varying requirements of use, the purpose being to provide an extension table having a number of supports for sustaining the extension sections when drawn outward, said supports being foldable 15 and automatic in operation so as to occupy an operative position and prevent over-balancing of the table.

A further purpose of the invention is the provision of an extension table in which the 20 leaves form part of the table so as always to be conveniently at hand when required for use, said leaves being mounted in a novel manner to admit of one extending over the other when the table is reduced to 25 the smallest size.

The invention consists of the novel features, details of construction and combination of parts, which hereinafter will be 30 more particularly set forth, illustrated in the accompanying drawings, and pointed out in the appended claim.

Referring to the drawings, forming a part 35 of the specification, Figure 1 is a view of an extension table as seen from the lower side, one-half of the table being extended. Fig. 2 is a central longitudinal section. Fig. 3 is a cross section on the line $y-y$ of Fig. 1. Fig. 4 is a longitudinal section on the line 40 $3-3$ of Fig. 1. Fig. 5 is a detail section on the line $w-w$ of Fig. 1. Fig. 6 is a detail perspective view of one of the sections of the table top. Fig. 7 is a detail perspective view 45 of a portion of the frame, cross piece and block.

Corresponding and like parts are referred 50 to in the following description, and indicated in all the views of the drawings, by the same reference characters.

The table comprises a rectangular frame 1, 55 legs 2 and a cross brace 3. In order to admit of the table being reduced to a compact form for storing and transporting the legs 2 are detachably connected with the frame 1 and the cross brace 3 is detachably connected 60 with the legs. Each of the legs has

a detachable foot 4, which is connected to the leg by means of a screw. Each end of the cross brace has an opening through which the screw extends, said end being clamped between the lower end of the leg 60 and the foot 4. When the parts are assembled the cross brace 3 is elevated from the floor by means of the foot pieces 4 and is likewise retained in place thereby. A cross piece 5 occupies a central position and 65 is secured at its ends to opposite rails or members of the frame 1. Blocks 6 are secured to the side rails of the frame opposite the ends of the cross piece 5 and have semi-circular recesses 7 formed in their inner 70 ends and opening through the upper sides, said recesses being designed to receive quadrant shaped lugs 8 provided near the inner corners of the sections forming the top of the table. 75

The table top comprises two sections 9 of like size and having a matching tongue and groove at their meeting edges to hold the sections in the same plane when in position. The table top is detachable and is 80 supported upon the leaves forming the extensions. When the extension leaves are drawn outward the sections 9 occupy the space formed between the innermost extensions and rest upon the blocks 6 and the 85 slides. The recesses 7 and lugs 8 prevent displacement of the sections 9 when placed in position.

The table comprises a plurality of extensions each consisting of a leaf or wing 90 and slides. Certain extensions are provided with supports or leg sections 10, which are connected to the sections to fold so as to be out of the way when the sections are moved inward. The supports or leg sections 10 are adapted to be thrown into operative position automatically by means of springs, thereby avoiding special care on the part of the person drawing the sections 95 outward to increase the length of the table. The leg sections 10 are connected to their supporting extensions by means of spring hinges. The leg sections are adapted to be folded by means of cords 11, each cord being connected at one end to a leg section 105 and secured at its opposite end to the leaf of the adjacent extension, said cord passing over a guide pulley 12 provided upon the extension to which the leg section is attached. The leg section is folded by swing- 110

ing the leaf to which the cord 11 is attached. The supports or leg sections 10 when folded occupy the space formed between the series of slides. In the present instance the table 5 is shown as embodying four extensions, two at each end. The supports or leg sections 10 are attached to the outer extensions so as to support the same when drawn outward. Two of the series of slides are fixed to the 10 frame of the table and are indicated at 13. The remaining slides are located upon opposite sides of the fixed slides and are movable with their respective leaves to which they are attached. The outer extensions 15 comprise leaves 14 and slides 15. Each of the inner extensions consists of a leaf 16 and slides 17. The leaf 14 is rigidly attached to the slides 15, whereas the leaf 16 is hinged or pivoted at its inner edge to the slides 17, 20 thereby leaving the leaf free to swing upward at its outer edge to which is secured the cord or flexible connection 11. When the extensions are moved inward the leaves 16 overlie the leaves 14. The grooves 18 25 of the several slides have their opposite end portions in different planes which are spaced apart a distance equal to the thickness of the leaves so that the leaves may occupy a superposed relation when the extensions are 30 moved inward. The portion of the blocks 6 projecting above the frame 1 is equal in depth to the combined thickness of the leaves 14 and 16 at the sides thereof, so that when the extensions are moved inward the 35 upper sides of the blocks 6 and the topmost leaves 16 are flush, thereby supporting the top or sections 9 in level position. A groove 19 is formed in the under side of each of the leaves 16 to receive the cord or flexible 40 connection 11 when the leaf 16 occupies a position above the leaf 14. The intermediate portion of each of the grooves 18 is inclined, the inclination being gradual so as not to interfere with the free movement 45 of the slides and extensions when drawing the sections outward or pushing them inward. When the extensions are slid or moved inward a catch 20 pivoted to the inner portion of each of the leaves 14 engages 50 the inner edge of the overlying leaf 16 so that when drawing outward upon the extension embodying the leaf 14 both extensions move outward together. When both extensions have been drawn outward to the 55 limit of the movement of the inner extension the catch 20 is disengaged from the leaf 16 when the outer extension may be drawn out-

ward to the limit of its movement and as the outer extension moves outward the leg section 10 gradually swings downward into 60 vertical position until when the outer extension is at the limit of its outward movement the leg section 10 attached thereto is in vertical position to form a support therefor. If preferred the catch may be released and the outer extension drawn outward independently of the inner extensions. It is to be understood that the extensions may be independently operated.

From the foregoing description, taken in 70 connection with the accompanying drawings, the advantages of the construction and of the method of operation will be readily apparent to those skilled in the art to which the invention appertains, and while I have 75 described the principle of operation of the invention, together with the device which I now consider to be the embodiment thereof, I desire to have it understood that the device shown is merely illustrative, and that 80 such changes may be made when desired as are within the scope of the claim appended hereto.

Having thus described the invention what is claimed as new, is:

In an extension table, the combination of 85 a frame, a top removably fitted upon the frame, a plurality of extensions, two sets of slides each comprising a plurality of members, the inner members being secured 90 to the frame and the slide members having grooves, the end portions of which are in different relative planes whereby when moving the slide members upon one another they at the same time have a vertical movement to admit of the extensions clearing one another, a foldable leg section pivotally connected to the outer portion of the outermost extension, a flexible connection secured to the lower portion of the folding 100 leg section and to the outer edge of the inner extension, and a catch attached to the under side of the inner portion of the outermost extension and adapted to engage the inner edge of the said inner extension to 105 cause both extensions to move together when pulling upon the outer extension.

In testimony whereof I affix my signature in presence of two witnesses.

ADOLPH R. BLOMBERG.
